UNITED STATES PATENT OFFICE.

CHARLES R. EDWARDS, OF PEKIN, ILLINOIS.

PUMP.

1,337,057.

Specification of Letters Patent. Patented Apr. 13, 1920.

Application filed November 23, 1917. Serial No. 203,532.

To all whom it may concern:

Be it known that I, CHARLES R. EDWARDS, a citizen of the United States, residing at Pekin, in county of Tazewell and State of Illinois, have invented certain new and useful Improvements in Pumps, of which the following is a specification.

My invention relates to an improvement in double-acting pumps and the present invention is an improvement on the disclosure 10 of Letters Patent No. 1,084,413, granted to me January 13, 1914.

One of the objects of this present invention is to make provision for having all 15 valves within the bore of the main cylinder, thus, making the cylinder more compact so that it is adapted to fit smaller well casings.

In the drawings:

20 Fig. 1 is a vertical sectional view.

Fig. 2 is a transverse section.

Fig. 3 is a transverse section through the plunger rod guides.

Fig. 4 is a bottom plan view of the 25 plunger rod guide.

Fig. 5 is a top view of the three-way valve, and,

Fig. 6 is a bottom plan view of the same.

A represents an outer cylindrical shell 30 of my improved double-acting pump, the same having internal screw threads at each end as shown in Fig. 1, and provided with channels K and L, for the passage of water which extends nearly throughout the length 35 of the cylinder.

A brass lining B, of cylindrical form is located concentrically within the cylinder A, where it is held centered by the enlargements 1, and reinforcements on the inner 40 wall of the cylinder as shown in Fig. 2, thereby dividing and separating the channels K and L.

Openings 2, 3, 4 and 5, are made through the lining B, as a means of communicating 45 with the channels K and L, at the upper and lower ends thereof.

Fitted within the lining B, is the plunger 50 which consists in a disk D, screwed to the threaded end of the plunger rod G, with the two leather washers P, the nuts H, and washers U, which hold the parts together and cause the plunger to fit the bore of the lining, water-tight.

At the upper end of the cylindrical shell 55 the plunger rod guide E, is located and within this guide there is a compartment or

liquid passage 7, which opens downwardly into the cylinder and registers laterally with the opening 2, leading into the upper end of channel K. This plunger rod guide 60 E, also has two liquid passages 8, as shown in Figs. 3 and 4, for liquid leaving the cylinder and a valve F, on the upper side of the plunger rod guide closes or controls the outlet and prevents a back flow of water 65 through these passages 8.

A three-way valve arrangement C, is located at the lower end of the cylinder A, and fitted in the lower end of the lining B, and with a flange which preferably extends around the extreme lower end of the lining B, the arrangement is held in position in lining B, by the cylinder cap R, which is screwed into the lower end of the cylinder as shown in Fig. 1. The opening 75 T, through this cylinder cap R, is also screw-threaded for attachment to the pipe fitting (not shown).

Referring back to the three-way valve arrangement C, it is divided into three compartments by means of the diagonal partitions W and Z, it being open at the bottom to communicate with the opening T, through the cylinder cap R, and having openings at its upper end which are controlled by valves 80 N and O, which open by the water pressure in opposite direction, and a valve M, at the lower end of the three-way valve arrangement opens inwardly and controls the passage of water through the opening 4, into 85 the lower end of channel K, whereas the valve O, controls the passage of water through the opening 5, and at the lower end of channel L, and the valve N, passes the water up into the cylinder above the three-way valve arrangement.

From the foregoing, it will be seen that all valves, channels, passageways and the like, are within the cylindrical circumferential area of outside cylindrical shell A, 100 which makes a compact arrangement of parts and adapts my present pump to fit small-sized well casings.

The operation is as follows:—

On the up stroke of the plunger, liquid is 105 drawn up into the lower end of the cylinder through valve N, thus filling the cylinder below the plunger with the completion of the up stroke of the plunger. When the plunger starts its downward stroke valve N, 110 is closed and at the same time, valve O, is forced open and the liquid in the cylinder is

forced out through opening 5, into the lower end of channel L, thence up through the latter and out through the outlet V, at the top into the pipe fitting above (not shown).

- 5 At the same time the plunger is lowering and forcing liquid through the channel L, it is also taking liquid into the upper end of the cylinder through opening 2, from channel K, so that when the plunger is down 10 the upper part of the cylinder above the plunger is filled with liquid.

As the plunger starts on its up stroke, the valve M in the lower end of the three-way valve arrangement C, leading to opening 4, 15 at the lower end of channel K, is closed, and the valve F, over the plunger rod guide E, is open at the same time and the liquid above the plunger is forced upward through passages 8, out of the cylinder at the outlet V, 20 so that the liquid is forced out by both the down stroke and the up stroke, thus creating a continuous flow while the pump is in operation.

In other words, while the plunger is lowering it is forcing liquid above cylinder from 25 the bottom and filling at the top, and when the plunger is being raised it is raising the liquid above the plunger from the cylinder and at the same time filling at the bottom.

30 I claim:—

1. A double-acting pump comprising an outer cylindrical shell, a cylindrical lining, means spacing the two apart and dividing the space therebetween into separate channels, the lining having openings at each end 35 into the channels, a three-way valve consisting of a flanged tube inserted into said cylindrical lining and divided into three compartments, two of which communicate 40 with two of the openings in the cylindrical shell, the other compartment forming an

opening longitudinally of the cylindrical shell, valves for said compartments, a plunger rod guide having passages to the space both above and below it and also a lateral 45 passage in communication with an opening into one of the channels, a valve for controlling the passage therebeneath, a plunger rod passing through said last-mentioned valve and plunger rod guide, and a plunger 50 on said rod.

2. A double-acting pump comprising an outer cylindrical shell, ribs extending longitudinally of its bore, a cylindrical lining fitted to the inner walls of said ribs where- 55 by the shell and lining are spaced apart and separate channels are formed therebetween, the lining having an opening at the upper and lower ends into each channel, a plunger rod guide at the upper end of the lining 60 which has passages therethrough to the space both thereabove and below and another lateral passage in communication with one of the channels, a valve above said plunger rod guide for controlling the upward 65 passage, a plunger rod slideable through said slide valve and plunger-rod guide, a three-way valve consisting of a flanged tube inserted into said cylindrical lining and divided into three compartments, two of which 70 communicate with two of the openings in the cylindrical shell, the other compartment forming an opening lengthwise of the cylindrical shell, valves for said compartments, and a cap having screw-threaded 75 connection with the outer cylinder and adapted to bear against the flanged end of the tubular member for retaining the latter in position.

In testimony whereof I affix my signature. 80

CHARLES R. EDWARDS.
